UNITED STATES PATENT OFFICE.

CLARENCE E. VAN AUKEN, OF CHICAGO, ILLINOIS, ASSIGNEE, BY MESNE ASSIGNMENTS,
TO COATS MACHINE TOOL COMPANY, INC., OF NEW YORK, N. Y., A CORPORATION OF
NEW YORK.

DUPLEX SAW.

1,277,786.

Specification of Letters Patent.

Patented Sept. 3, 1918.

Application filed June 12, 1916, Serial No. 103,159. Renewed July 20, 1918. Serial No. 245,967.

To all whom it may concern:

Be it known that I, CLARENCE E. VAN AUKEN, a citizen of the United States, residing at Chicago, county of Cook, State of Illinois, have invented a certain new and useful Improvement in Duplex Saws, and declare the following to be a full, clear, and exact description of the same, such as will enable others skilled in the art to which it pertains to make and use the same, reference being had to the accompanying drawings, which form a part of this specification.

In the ordinary hack saw for sawing metal, there is a single blade which can cut on only one stroke of each cycle, the saw therefore doing effective work during only half the time that it is running.

The primary object of the present invention is to produce a simple and efficient sawing machine of the reciprocating type which shall saw effectively on all strokes and not simply on half the strokes; thus giving double the capacity of a single saw.

In carrying out my invention I employ two opposed saw blades which reciprocate together on opposite sides of the work, have their teeth arranged in opposite directions so that one will cut on the forward stroke and the other on the back stroke and are movable from and toward each other to permit them to be opened to receive a piece of work and to approach each other as they saw through the work from opposite sides.

In order to prevent waste of material and producing uneven ends, it is necessary that the saws lie in the same plane. Viewed in one of its aspects my invention may be regarded as having for its object to produce a simple means for maintaining two opposed relatively movable saws in accurate alignment with each other.

Where two opposed saws lying in the same plane are employed it is of course not practicable to let the opposed teeth approach each other so closely that they will cut completely through the work without engaging with each other and destroying each other, because the ordinary commercial saws that are used will vary considerably in width when new and of course they will diminish in width while in use, so that even if the saws can be so accurately made that the teeth would just cut through an interposed piece of work, this condition would not continue for any considerable

length of time after the saws were in use. The mechanism must therefore be so constructed that the teeth of the opposed saws will at all times remain at some distance apart so as to avoid the danger of destruction of the saws through engagement of the teeth of one with those of the other.

Viewed in one of its aspects my invention may be said to have for its object to produce a simple and efficient construction and arrangement by means of which two opposed saws may be made to pass completely through an interposed piece of work, in registration with each other, without danger of bringing the teeth in contact with each other and without leaving an unsevered portion at the middle of the work.

Viewed in another of its aspects my invention may be said to have for its object to produce a simple and novel saw in which the pressure on a saw member during a cutting stroke may be easily and conveniently regulated within wide limits.

Viewed in another of its aspects, my invention may be said to have for its object to produce a simple and efficient arrangement by means of which a continuous flow of cooling and lubricating fluid over a saw or saws will be maintained during the operation of a sawing machine.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Fig. 1 is a front view of a sawing machine arranged in accordance with my invention, the hollow base or frame being shown in section with the front wall omitted;

Fig. 2 is a vertical section through the machine taken at right angles to the plane 100 of Fig. 1;

Fig. 3 is a front elevation on an enlarged scale of a portion of the mechanism for controlling the pressure on the saw blades and feeding them toward each other;

Fig. 4 is a section taken approximately on line 4-4 of Fig. 3;

Fig. 5 is a section taken approximately on line 5-5 of Fig. 3;

Fig. 6 is a front elevation of the saw 110

frames and some of the associated parts occupying the positions illustrated in Fig. 1 with the front portions of the feeding clutch removed and exposed parts normally concealed;

Fig. 7 is a view similar to Fig. 6 illustrating the saws spread apart to receive a piece of work;

Fig. 8 is a vertical section on an enlarged 10 scale through a portion of one of the saw frames, showing the means for feeding the lubricating and cooling fluid;

Fig. 9 is a side view on an enlarged scale of the friction connection between the saw 15 frames and the mechanism for feeding the saws toward each other;

Fig. 10 is a section taken approximately on line 10—10 of Fig. 9; and

Fig. 11 is a front view of the device illustrated in Fig. 9 looking at the device from the right hand side of the latter figure.

Referring to the drawings, 1 represents the supporting frame or base of the machine in the form of a casing or shell adapted to contain a considerable quantity of cooling and lubricating fluid. On the rear side of the casing is a driving device illustrated as taking the form of a pulley, 2, whose shaft projects into the casing and is provided with a crank, 3. Below the crank is fixed a vertical guide, 4, on which is slidably mounted a suitable cross head, 5. Between the crank and the cross head is a connecting rod, 6; the arrangement being such that when the crank is rotated the cross head is reciprocated in the vertical direction.

Arranged within the casing are two saw frames pivotally supported at their lower 40 ends on a wrist pin, 7, carried by the cross head, this wrist pin being conveniently an extension of the journal engaged by the lower end of the connecting rod, 6. Each of the saw frames consists conveniently of a 45 lower member in the form of a web-like casting, 8; the two castings lying in the same plane with their inner edges adapted to be brought in close proximity to each other. Extending upwardly along the outer 50 edge of each of the castings is a post, 9, rigidly secured to the casting and projecting upwardly out of the top of the casing; each post being provided at its upper end with a head, 10, projecting inwardly toward 55 and adapted to engage with the head on the opposite post when the two frames are swung together. Saw blades, 11 and 12, such as are ordinarily employed in hack saws, are arranged between the heads and 60 the upper inner corners of the castings 8; the saws being reversely arranged so that the teeth of one are set to cut on the up stroke while the teeth of the other are arranged to cut on the down stroke. The 65 parts are so proportioned that when the

heads 10, or any suitable stop devices on the two frames which limit the movement of the frames toward each other, come into engagement, there will be a considerable space between the teeth of one saw and 70 those of the other; this space insuring that the teeth of the opposed saws will at no time come in contact with each other and damage the machine.

If the saws are operated in a dry state 75 they must be run very slowly in order that they will not become overheated; and, by providing for the effective cooling and lubrication of the saws the capacity of the machine is substantially doubled. Therefore, in order that the machine may be run at a high speed, I have provided means for effectively cooling and lubricating the saws. To this end I use the hollow frame of the machine as a reservoir for any usual or 80 suitable cooling and lubricating liquid and, in order to avoid the use of a separate pump, I make pumps out of the frames of the saws. This feature is best illustrated in Fig. 8. Referring to this figure, it will be seen that 85 the post 9 consists of a pipe or tube projecting through and screw threaded into or otherwise secured to an ear, 13, on the casting 8, a valve casing, 14, containing an inwardly-opening check valve, 15, being secured to the lower end of the post and, where the post is screwed in place, serving conveniently as a lock.

Near the upper end of the tubular post is an opening, 16, extending out through 100 the side registering with a passage, 17, extending transversely through the head and communicating with a vertical bore, 18. In the bore 18 is arranged a vertically adjustable piece, 19, to the lower end of which is 105 attached the upper end of the saw blade. The member 19 has a sliding fit in the bore 18 and is provided on its upper end with a screw threaded part, 20, on which is a nut, 21, resting upon the top of the head 10 and 110 forming a closure for the upper end of the bore 18. The member 19 is provided with suitable passageways adapted to register with the passage 17. In the arrangement shown, these passageways are formed by 115 cutting in the member 19 a series of peripheral grooves, 22, extending around the same just below the screw threaded portion, together with a longitudinal groove, 23, extending from the seat for the saw blade up 120 through the flanges or collars, 24, produced by the grooves, 22. This arrangement permits the member 19 to be adjusted vertically for a considerable distance without interrupting communication between the passageways 17 and 23 and without making the bearing of the member 19 in the head too short; the collars or flanges, 24, acting as effective bearing members.

The operation of the pumping device is 130

as follows: As the saw frames move downward in the lubricating liquid, some of the liquid is forced up into the hollow posts and is retained there. After a sufficient number of strokes have been made to fill the tubular posts, the next succeeding stroke will cause an overflow of the lubricating and cooling liquid through the passages in the heads and the saw supports, 19, the liquid being discharged directly upon the upper ends of the saws so that they are effectively cooled and lubricated.

The rate at which the cooling and lubricating fluid is delivered to the saws may be controlled by suitable valves which, in the arrangement shown, take the form of screw threaded plugs 25, extending down through the heads 10 into the upper ends of the hollow posts and governing the effective area of the opening 16.

The saws are kept accurately in alinement with each other by means of a bar, 26, extending transversely across the saw frames, preferably across the members 8 thereof; this bar being provided with suitable pin and slot connections which permit the saw frames to be swung from and toward each other about their pivotal axes without being capable of relative movements in a direction to bring the saws out of alinement with each other. In the arrangement shown, the bar is provided with two elongated slots, 27, through which pass headed screws, 28, supported at their inner ends by the members 8.

On the outer side of each saw frame is a lever, 30, which preferably has a grooved roller, 31, engaging with the corresponding post 9 to form a guide for the reciprocating frame as well as a pressure member adapted to feed the saw into the work. These levers may take any suitable form as long as the parts which engage the saw frames are adapted to swing from and toward each other. In the arrangement shown, each of the levers consists of a simple bar pivotally supported between its ends, as indicated at 32, on the upper portion of the stationary frame of the machine. To the lower end of the lower arm of each lever is connected a bar which may conveniently be a simple rectangular piece as indicated at 33; the two bars lying side by side and overlapping each other for the greater portion of their length when the saws are close together. If desired, each bar may be provided on its inner free end with a saddle or clip, 34, slidably engaging with the other bar and thus causing the two bars to be held together so as to be, 60 slidably one upon the other. Embracing the middle of the overlapping bars, 33, is a gripping device adapted to grip either bar securely and leave the other bar entirely free to reciprocate independently of the gripping device. As best shown in Figs. 4 to 7 in-

clusive, the gripping device consists simply of a housing, 35, surrounding the bars and containing in the upper portion thereof two blocks, 36, held in place by a pin, 37, passing through the housing and through the blocks midway between the ends of the latter and permitting the blocks to rock, each in the plane of one of the bars 33. In the housing, on the under side of the bars, are a pair of short blocks, 38 and 39, respectively, the block, 38, underlying the front bar and being pivotally supported at its left hand end as indicated at 40 while the block 39 underlies the rear bar and is pivotally connected to the gripper casing or housing at its right hand end as indicated at 41. It will be seen that by reason of the disposition of the pivotal points, 37, 40 and 41, at the three corners of a triangle, a tilting of the gripping device in one direction will cause one of the long blocks and one of the short blocks to grip one of the bars, while the blocks of the other set simply yield and leave the corresponding bar free. In other words, viewing the device as illustrated in Fig. 7, if the gripping device be turned in the clockwise direction or if it be attempted to turn it in that direction, the tendency is to make the vertical distance between the pivotal points 37 and 40 smaller than it is in the neutral position and at the same time make the vertical distance between the pivotal points 37 and 41 greater than it is in the neutral position. Thus the front bar will be gripped and the other bar will be left free. If the gripper be tilted in the opposite direction, a reversal of the process just described takes place.

I employ the gripper, just described, for the purpose of alternately holding the saws against the work and feeding them into the work. To this end I have provided the following mechanism: On the stationary frame of the machine, at one side of the center, is placed a rocker device, 42, connected by a link, 43, to the lower end of the gripper. The rocker device may consist of a simple lever pivotally supported between its ends as indicated at 43^a, the lower end being a simple arm and the upper end a hub-like projection, 44, through which extends a transverse actuating arm, 45; the actuating member being preferably slidable in the member 44 for a purpose which will hereinafter appear. The actuating arm plays between a pair of stops, 46 and 47, best shown in Fig. 1, it being moved up and down by means of a suitable driving connection with the saw frames. This driving connection conveniently consists of a connecting rod extending from the wrist pin 7 to a sleeve or block, 48, attached to the actuating arm; the connecting rod being extensible and having a frictionally held slip joint. With this arrangement, as the saws move up and down, 130

the actuating arm oscillates and produces an oscillating movement in the rocker device 42. The parts are so proportioned that when the actuating arm lies halfway between the stops 46 and 47, the gripper is in its neutral position and the saw frames may be swung apart or toward each other without encountering resistance. When the actuating arm is carried toward the lower stop it causes the gripper to act on the bar associated with the right hand saw which is therefore pushed inwardly. When the actuating arm is moved from its neutral position toward the upper stop, the left hand saw is acted upon and the right hand saw is left free. It will be seen that as the saws travel down the connection between the arm 45 and the saw frames causes the arm to be swung down and thus causes the right hand saw to be fed into the work while as the saws move upwardly the actuating arm is moved in a direction to cause the left hand saw to be fed into the work. The right hand saw, 11, is therefore set so that it will cut on the down stroke while the left hand saw, 12, is set so that it will cut on the up stroke.

It will be seen that the gripper does not merely grip and hold the bars associated with the saw-controlling levers but actually feeds these bars in the proper direction to cause the saws to feed into the work. Furthermore, when the saw frames are brought together as shown in Figs. 1 and 6 and the machine is set in operation the center line between the saws will be caused to oscillate across the vertical center line of the machine; this peculiarity enabling the machine to saw entirely through a piece of work even though the saw blades be spaced a considerable distance apart.

The connecting rod with a slip joint affords a simple means for producing a steady pull or push on the actuating arm which will insure that the saws will at all times be fed into the work from one end of the stroke to the other.

In the arrangement illustrated, the connecting rod is made of an upper member, 50, pivotally connected at its upper end to a member 48 on the actuating arm, together with a lower member, 51, which is carried at its lower end on the wrist pin, 7. To the lower end of the member 50, as best shown in Figs. 9, 10 and 11, is fixed a piece, 52, having laterally projecting arms, 53, at the four corners. Lying in rear of the member 52 is a piece, 54, generally U-shaped, having its arms lying against the side edges of the body of the member 52 and having laterally projecting parts, 55, at the free ends of its arms extending between the arms at the top of the member 52 and the arms at the lower end thereof. Each of the arms, 53, is recessed on its front side to form a

pocket as indicated at 56. The members 52 and 54 are held together by means of leaf springs, 57, each of which or each set of which extends from one of the upper pockets, 56, into the corresponding lower pocket in rear of one of the flanges or extensions, 55, on the member 54. The free end of the connecting rod member 51 is thrust between the members 52 and 54, spreading them apart against the tension of the springs and being frictionally clamped thereby to the upper connecting rod member 50. The friction on the joint may be regulated by varying the number of leaves in each spring or the size of the spring if it should be made only of a single leaf. It will be seen that the friction coupling or joint has the function of compensating for the difference between the extent of movement of the upper end of the connecting rod and the extent of movement of the lower end of the connecting rod, the upper end moving through a much shorter distance than the lower end when the machine is running idle, and the further function of permitting the actuating arm, 45, to lag behind its normal rate of movement as the saws are fed into the work, thus at all times keeping a pressure on each saw while it is on a sawing stroke, this pressure depending upon the strength and tension of the springs 57. The pressure on the saws and the rate at which they will feed into the work is further regulated by moving the actuating rod, 45, axially through the member 44 of the rocker device; thus varying the distance between the pivotal axis, 43, of the rocker device and the point of application of the pull or thrust from the connecting rod.

It is desirable that the gripping device for feeding and holding the saws into the work be returned automatically to a central idle position when free to do so. To this end I have provided a yieldable centering device consisting simply of two spring pressed shoes, 60, lying on opposite sides of a pin or projection, 61, projecting forwardly from the gripper casing 35. In the arrangement shown, the centering shoes are mounted on the inner ends of short alined horizontal shafts, 62, each mounted on the lower ends of two separated downwardly projecting arms, 63, of a bracket, 64; there being four of these arms spaced apart from each other; the shoes and the pin, 61, lying between the two innermost arms and each of the shafts, 62, being slidably supported in one of the inner arms and the corresponding outer arm. On each of the members 62, between the two arms in which it is supported, is a spring, 65, bearing at one end against the corresponding outer arm and at its other end against a shoulder, 66, on the shaft. Movement of the gripping device in either direction must therefore take place against the

tension of one of the springs 65 which, when free to do so, returns the gripper device to its central position.

Whenever either of the bars 33 is released by the gripping device, the corresponding saw controlling lever is free to be oscillated at will and, in order to prevent the levers at such times from being thrown outwardly out of operative relation to the saw frames 5 and thus prevent the saws from being properly fed, I provide springs, 70, arranged between the levers 30 and the stationary framework of the machine and tending constantly to swing the upper ends of the levers 10 toward each other; these springs having nothing to do with the pressure on the saws while the latter are on the cutting stroke, because such pressure will be very much greater than the comparatively slight pressure 15 that could be produced by the holding springs. In other words, the feeding pressure on the saws is a positive drive from the main shaft modified by the friction joint in the connecting rod and the lever ratios between the main shaft and the points of contact 20 between the levers 30 and the saw frames, while the springs, 70, exert simply a slight pull which will hold the levers 30, while freed from the gripping device, 25 against the corresponding saw frames and thus insure that the saws will take hold at the very beginning of the sawing strokes.

Normally when there is no work of the machine and it stands idle, the heads of the 30 saw frames are in contact with each other as shown in Fig. 6. When it is desired to introduce a piece of work between the saws, the saw frames are grasped at their upper ends and drawn apart as shown in Fig. 7, 35 thus permitting the work, 71, which is to be sawed to be placed between the saw blades.

On the stationary frame in rear of the saw frames there is arranged a work holding clamp, 72, of any usual or suitable construction.

As heretofore explained, the pressure on the saws is controlled both by the friction joint in the connecting rod between the actuating arm 45 and the wrist pin 7 and the 40 position of this arm in the rocker device 42. The ordinary variations in pressure that the workman will desire to make, depending upon the nature of a particular piece of work, will be made simply by pushing the 45 actuating arm, 45, in or out, the adjustment of the friction joint in the connecting rod being made only to take care of the general nature of the work that the machine has to do. A simple means for holding the actuating arm, 45, in any adjusted position consists in providing it with a series of shallow recesses or pockets, 73, distributed lengthwise thereof, and placing in the member 44 of the rocker device a spring-held plunger, 74, adapted to seat itself in any one of the

pockets or recesses with which it may be brought into registration and yieldingly hold the actuating arm with sufficient pressure to prevent accidental displacement while leaving the arm free to be moved back and forth by the workman.

In the drawings I have illustrated only a single design of machine that has been found to work very successfully in practice and, for the sake of brevity I have confined the 75 detailed description to this one form of machine. It will of course be understood, however, that the details of the machine may be widely varied without departing from the principle of my invention and I therefore do 80 not desire to be limited to the details of the particular machine illustrated; but intend to cover all forms and arrangements which come within the terms of the definitions of my invention constituting the appended 85 claims.

I claim:

1. In a machine of the character described, two opposed, alined, reciprocable saws movable from and toward each other independently, pressure devices acting on the saws for the purpose of moving them toward each other, and means for acting alternately on said pressure devices during successive strokes of the saws so as to release one of the saws from the work and force the other toward the common center throughout the working stroke.

2. In a machine of the character described, two opposed alined, reciprocable 100 saws pivotally supported so as to be capable of swinging independently from and toward each other; and means for acting alternately on said saws during successive strokes thereof to feed one of the saws toward the other 105 and simultaneously release the latter from the work.

3. In a machine of the character described, two opposed, alined, reciprocable saws supported so as to be movable lengthwise in unison and from and toward each other independently; and means acting alternately on said saws during successive strokes to feed one toward the other and simultaneously release the latter.

4. In a machine of the character described, two opposed alined, reciprocable saws supported so as to be movable lengthwise in unison and from and toward each other independently, and driven means for feeding one of the saws into the work throughout one stroke of each cycle and feeding the other saw into the work throughout the other stroke of each cycle.

5. In a machine of the character described, two opposed, alined, reciprocable saws movable from and toward each other, lever devices acting on said saws for the purpose of feeding them toward each other, and means for acting alternately on said 125

lever devices during successive strokes of the saws to retract one of them and place the other in motion to feed the corresponding saw.

5 6. In a machine of the character described, two opposed, alined, reciprocable saws movable from and toward each other, levers acting on said saws for feeding them toward each other, parallel overlapping bars 10 secured to said levers, a gripper device engaging the overlapping portions of said bars and adapted to be moved in one direction to grip one of the bars and to be moved in the other direction to grip the other bar, 15 and means for moving said gripper device back and forth in time with the reciprocation of the saws.

7. In a machine of the character described, two opposed, alined, reciprocable 20 saws movable from and toward each other; a driving member for reciprocating said saws, pressure devices acting on the saws for the purpose of moving them from and toward each other; and means including 25 a friction clutch between said pressure devices and said driving member for acting alternately on said pressure devices.

8. In a machine of the character described, two opposed, alined, reciprocable 30 saws movable from and toward each other; a driving member for reciprocating said saws; mechanism acting on the saws to feed one of them toward the other and release the latter from the work during one stroke 35 of each cycle and reverse the operation on the other stroke of each cycle; and a driving connection between said mechanism and said driving member including a friction clutch.

40 9. In a machine of the character described, two opposed, alined, reciprocable saws movable from and toward each other; a driving member for reciprocating said saws; mechanism acting alternately on said 45 saws so as to feed one into the work on one stroke of each cycle and to feed the other saw into the work on the other stroke of each cycle; an actuating lever for said mechanism; and a connecting rod between said 50 lever and said driving member having a frictionally held joint permitting the connecting rod to become lengthened or shortened.

55 10. In a machine of the character described, two opposed, alined, reciprocable saws movable from and toward each other; a driving member for reciprocating said saws; mechanism acting alternately on said saws so as to feed one into the work on one 60 stroke of each cycle and to feed the other saw into the work on the other stroke of each cycle; an actuating lever for said mechanism; a connecting rod between said lever and said driving member having a frictionally held joint permitting the connecting 65

rod to become lengthened or shortened; and means for varying the length of the lever arm between the point of attachment of the connecting rod to the actuating arm and the point of application of power from the actuating arm to the aforesaid mechanism. 70

11. In a machine of the character described, two opposed, alined saw frames pivotally supported so as to be capable of swinging from and toward each other, a bar 75 extending across said frames and engaging with corresponding sides thereof, and pin and slot connections between said bar and said frames permitting the frames to be swung from and toward each other and at 80 the same time be held in alinement with each other.

12. In a machine of the character described, a reciprocable saw frame, a reservoir 85 for cooling and lubricating liquid in position to be entered by one end of the saw frame as it reciprocates, a saw in said frame, said frame having a passageway extending through the same from the aforesaid end to the upper end of the saw, and an inwardly opening check valve located at the inlet end of said passageway. 90

13. In a hack saw machine, the combination of a saw frame, means for reciprocating the same up and down, and a receptacle for 95 fluid wherein the lower part of the frame operates, said frame being constituted as a pump to elevate fluid from the reservoir to flow downward over the blade.

14. A double hack-saw machine, comprising a stand having a work support on its upper portion, two opposed vertically-reciprocable saw-frames mounted at opposite sides of the center of the stand to receive the work between them, driving means on the stand wherewith the lower parts of the saw-frames are connected to effect their reciprocation, and mechanism operated by said driving means for forcibly feeding the saws alternately toward the common center throughout their respective working strokes. 100

15. A double hack-saw machine, comprising a stand having a work support on its upper portion, two opposed vertically-reciprocable saw-frames mounted at opposite sides of the center of the stand to receive the work between them, driving means on the stand wherewith the lower parts of the saw-frames are connected to effect their reciprocation, oscillatory intermittent-grip feed means operated by said driving means for forcing the saw-frames alternately toward the common center throughout their respective working strokes, and a yielding connection through which the feed mechanism is operated by the 110 driving means of the machine. 120

16. A double hack-saw machine, comprising a stand having a work supper on its upper portion, two opposed vertically-reciprocable saw-frames mounted at opposite sides 130

of the center of the stand to receive the work between them, driving means on the stand wherewith the lower parts of the saw-frames are connected to effect their reciprocation, 5 continuously-acting intermittent-grip feed mechanism for the saw-frames, and connections including a friction slip joint between said feed mechanism and the driving means whereby the saws are alternately fed forcibly toward the common center throughout 10 their respective working strokes.

17. A double hack-saw machine, comprising a rectilinearly-guided carriage, driving means for reciprocating the same, opposed saw-frames carried by the common carriage and movable laterally thereon toward and from each other, and constantly and yieldingly driven feed mechanism operating alternately upon said frames to force first one 20 and then the other repeatedly toward the common center while executing their respective working strokes.

18. A double hack-saw machine, comprising two opposed saw-frames adapted to receive the work between them, driving mechanism for reciprocating the saw-frames, a feed device for forcing said saws alternately toward the common center throughout their respective working strokes, a positive drive 30 for said feed device, and a friction slip joint for modifying such positive drive so as to produce a substantially uniform pressure on the saws.

19. A double hack-saw machine, comprising opposed saw-frames movable lengthwise in the same directions and independently movable laterally, supporting and guiding means for the saw-frames, oscillating intermittent-grip feed mechanism operative alternately upon the saw-frames to force them individually toward the common center while executing their respective working strokes, and power means for reciprocating the saw-frames and operating the feed 45 mechanism in proper time.

20. A double hack-saw machine, comprising a vertically-guided common carriage and means for reciprocating the same, two opposed saw-frames pivoted to said carriage 50 and adapted to be swung from V-relation toward parallelism as the cutting proceeds, pressure devices engaging the saw-frames as the latter travel relatively thereto, and feed mechanism acting alternately upon said 55 pressure devices.

21. A double hack-saw machine, comprising opposed saw-frames; mechanism for driving the same, and a constantly-driven oscillating intermittent-grip feed for forcing the saw-frames alternately toward the common center while executing their respective working strokes.

22. A double hack-saw machine, comprising opposed saw-frames, mechanism for 65 driving the same, oscillating intermittent-

grip feed means for forcing the saw-frames alternately toward the common center while executing their respective working strokes, and additional means operative inwardly upon the saw-frames to insure proper positioning for the working strokes. 70

23. A double hack-saw machine, comprising a driving means, opposed vertically-reciprocating saw-frames pivotally connected at their lower portions with said driving 75 means, being initially in diverging relation and swinging inward toward the common center as the cutting proceeds, pressure devices for acting upon the saw-frames as the latter travel relatively thereto on their working strokes, overlapping bars connected with the pressure devices, and a common oscillating feed device connected with the driving means and acting upon said bars. 80

24. A double hack-saw machine, comprising vertically-reciprocating opposed saw-frames, means for driving the same, pressure devices in contact with which the saw-frames travel, overlapping bars connected 90 with the pressure devices, and a common oscillatory intermittent-grip driven feed device upon the overlapping portions of the bars. 95

25. A double hack-saw machine, comprising vertically-reciprocating opposed saw-frames, means for driving the same, pressure devices in contact with which the saw-frames travel, overlapping bars connected with the pressure devices, a common oscillatory intermittent-grip driven feed device upon the overlapping portions of the bars, and means tending to centralize the feed device. 100

26. A double hack-saw machine, comprising opposed substantially upright saw-frames mounted so as to be independently movable laterally, means for reciprocating the saw-frames, and mechanism including oscillatory driven intermittent-grip members for forcing the saw-frames alternately toward the common center while executing their working strokes, the said mechanism including means whereby each saw-frame is released from the work while on its idle 115 stroke. 105

27. A double hack-saw machine, comprising two pivoted saw-frames adapted to receive the work between them in V-relation, mechanism for reciprocating the saw-frames 120 up and down, pressure devices adapted to bear upon the frames as they travel relatively thereto, intermittent-grip mechanism driven in phase with the reciprocation of the saw-frames and acting through the pressure devices to force the frames alternately toward the common center throughout their working strokes, means whereby said mechanism also moves the pressure devices away 125 from the frames alternately, during their 130

idle strokes, the saws then swinging outward by gravity, and springs connected with the pressure devices for bringing each saw-frame back to the work in readiness for 5 each working stroke.

28. A double hack-saw machine, comprising opposed saw-frames, driving means for reciprocating the same, constantly-driven oscillatory intermittent-grip feed mechanism for forcibly feeding the saws alternately toward the common center while exe-

cuting their respective working strokes, a friction slip joint through which said feed mechanism is driven, pressure devices through which the feed mechanism acts 15 upon the saw-frames, and springs also acting upon the pressure devices to bring the saws to the work in readiness for the successive cutting strokes.

In testimony whereof I sign this specification.

CLARENCE E. VAN AUKEN.
